CLAIM

The ornamental design for a deep fryer, as shown and described.

DESCRIPTION

FIG. 1 is a perspective view of a deep fryer showing our new design;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view.

The broken lines are shown for illustrative purposes only and form no part of the claimed design.
